UNITED STATES PATENT OFFICE.

MAX HIMMELFARB, OF BROOKLYN, NEW YORK.

DESIGN FOR A COMBINED TRAY AND CHECKERBOARD.

Application filed January 20, 1926. Serial No. 16,187. Term of patent 7 years.

To all whom it may concern:

Be it known that I, MAX HIMMELFARB, a citizen of the United States of America, residing at Brooklyn, Kings County, State of New York, have invented a new, original, and ornamental Design for a Combined Tray and Checkerboard, of which the following is a specification, reference being had to the accompanying drawing, forming part here-

of, which illustrates a perspective view showing my new design.

I claim—

The ornamental design for a combined tray and checkerboard as shown.

Signed at New York city, New York, this 2nd day of January, 1926.

MAX HIMMELFARB.
